UNITED STATES PATENT OFFICE.

WILBUR A. COMSTOCK, OF BETHEL, CONNECTICUT.

HEAT-REGULATING APPARATUS.

No. 872,714.

Specification of Letters Patent.

Patented Dec. 3, 1907.

Application filed May 1, 1907. Serial No. 371,316.

To all whom it may concern:

Be it known that I, WILBUR A. COMSTOCK, a citizen of the United States, residing at Bethel, in the county of Fairfield and State of Connecticut, have invented certain new and useful Improvements in Heat-Regulating Apparatus; and I do hereby declare the following to be a full, clear, and exact description of the invention, such as will enable others skilled in the art to which it appertains to make and use the same.

My invention relates to steam heat regulating apparatus, and consists in the arrangement of parts and combination of parts hereinafter fully described and then particularly pointed out in the claims which conclude this application.

The object of my invention is to provide an apparatus which shall not only regulate the heat but also will be capable of regulating the steam pressure so that the latter may be maintained at a fixed gage until sufficient heat has been obtained.

In the accompanying drawing Figure 1 is an elevation showing a furnace equipped with my improved apparatus, and Fig. 2 a detail enlarged elevation of the pipe damper regulating wheel.

Similar numbers of reference denote like parts in both figures of the drawing.

1 is any suitable furnace having the usual draft door 2 and provided at the top with a pipe 3, which serves as the outlet for the smoke and products of combustion and is disposed horizontally and extends into any suitable chimney 4.

5 is an inlet which leads into the flue in the chimney 4 and which can be closed by a door 6 hinged at the top to the inlet, and 7 is a lever pivoted at or about its middle portion to the side of the chimney and having its rear extremity connected to the bottom of said door by means of a chain 8.

9 is a chain which is secured to the inner end of the lever 7, the lower portion of which chain depends below said lever and is attached at its end to a weight 10. This chain 9 also extends above the lever 7 and is led in a horizontal plane over guide pulleys

11, 12, that are secured to any stationary object, as for instance, the ceiling of a cellar, said chain depending from the pulley 12 and having its extremity attached to a weight 13 which is capable of sliding on a beam 14 which latter is secured in the usual manner to the expandible and collapsible

diaphragm 15 that is in direct communication, in the usual manner, with the steam chamber of the furnace.

A double angle iron, *a*, is rigidly mounted 60 on the diaphragm case *b*. Plunger *c*, passes down through this case with its lower end against the diaphragm and the beam 14, is pivoted at *d*, to the front arm *e*, of the angle iron and extends freely through vertically 65 disposed elongated openings in the plunger and in the rear arm *f*, of the angle iron so that when the steam pressure raises the diaphragm the plunger will be forced upwardly, and will swing the pivoted beam so 70 that its rear will be elevated and its front depressed.

16 is a chain one end of which is connected with the outer end of the beam 14 and is led down around a pulley 17 that is secured 75 to the bottom of the draft door 2, this chain thence extending upwardly and over any suitable pulley 18 attached to the ceiling of the cellar and connected in the usual and ordinary manner to any suitable thermostat 80 apparatus, which latter I have designated 30, and shown in diagram since it forms no part of my present invention.

19 is a chain the outer extremity of which is connected to said thermostat apparatus, 85 which chain extends over a suitable pulley 20 depending from the ceiling of the cellar, the inner end of said chain depending from said pulley and secured to a door 21 which normally closes an inlet 22 which affords an 90 external check-draft.

23 is a shaft journaled in opposite sides of the horizontally disposed portion of the pipe 3, and 24 is a damper (shown in dotted lines) secured to said shaft within said pipe. 95

Fixed upon one end of the shaft 23 outside the pipe is a wheel 25 which has a hub 26, and 27 is a belt of any suitable material one end of which is secured to said hub and wrapped around the same while the upper or 100 free end of this belt is secured to the chain 19.

28 is a chain the upper end of which is attached to the periphery of the wheel 25, while the chain itself depends from said wheel and has secured to its lower extremity 105 a weight 29.

Before entering into a description of the operation of my improvement, I desire to say that the latter is applicable to both steam and hot water heating systems and in 110 each instance the expandible and collapsible diaphragm will be utilized in the usual man-

ner, its action being governed in the one case by the pressure of the steam and in the other by hydrostatic pressure.

The operation of my improvement is as follows:—The weight 13 is adjusted on the beam 14 to determine the amount of steam pressure required to elevate said beam to a horizontal position. When heat is required the thermostat is operated in the usual manner, thereby causing a pull to be exerted on the chain 16 to open the draft door 2, and also causing the chain 19 to be slackened, and at this time the damper 24 will be opened and the doors 6, 21, closed. When the pressure of steam, determined by the adjustment of the weight 13, has been obtained, said weight will thereby become elevated and the beam 14 brought to substantially a horizontal position, thus closing the door 2 and opening the door 6, and the steam pressure will remain constant until the degree of heat required has been obtained, the damper 24 remaining open and the door 21 remaining closed during this time. When the thermostat 25 operates, after the required degree of heat has been obtained, the chain 16 will thereby be slackened while the chain 19 will be tightened and pulled thereby opening the door 21 and closing the damper 24, the slackening of the chain 16 of course allowing the draft door 2 to remain closed while the weight 13 will drop thereby operating to close the door 6.

In my improvement it will be noted that the door 6 is below the point at which the furnace communicates with the chimney and is of course beyond the damper, while the door 21 is on the opposite side of the damper, and this arrangement is very effective in 40 checking combustion.

It will be noted that when the elevation of the beam 14 has caused the closing of the draft door 2 and has checked the main draft by the opening of the door 6, the further heat required will be obtained at a stationary steam pressure, and this means a great saving in fuel. It will further be noted that I have made no fixed connection between the chain 16 and the draft door 2 but that the 45 chain travels freely over a pulley secured to this door, and I obtain thereby a much better co-active operation of the diaphragm beam and draft door.

Having thus described my invention what I claim as new and desire to secure by Letters Patent is:

1. In a heat regulating apparatus, the combination of a steam furnace having a draft door at the bottom and provided with 55 an expansible and collapsible diaphragm connected with the steam chamber, a beam operatively connected with said diaphragm and having thereon a slidible weight, a chimney

provided in its lower portion with an opening leading into said chimney, a door closing said opening, a pipe whereby the products of combustion pass from the furnace into said chimney at a point above the door therein, a pivoted lever, a chain connecting the outer end of said lever to said chimney door, a second 65 chain connected to the inner end of said lever and depending therefrom and having a weight secured to its lower extremity, said second chain being passed up over suitable pulleys and thence depending and secured to 70 the beam weight, a third chain extending over a suitable overhead pulley and thence downwardly around a pulley secured to said draft door and thence upwardly and secured to said beam, and a thermostat connected to 75 said third chain for operating the latter.

2. In a heat regulating apparatus, the combination of a steam furnace having a draft door at the bottom and provided with an expansible and collapsible diaphragm connected with the steam chamber, a beam operatively connected with said diaphragm and having thereon a slidible weight, a chimney provided in its lower portion with an opening leading into said chimney, a door closing said 85 opening, a pipe whereby the products of combustion pass from the furnace into said chimney at a point above the door therein, a pivoted lever, a chain connecting the outer end of said lever to said chimney door, a second chain connected to the inner end of said lever and depending therefrom and having a weight secured to its lower extremity, said second chain being passed up over suitable 90 pulleys and thence depending and secured to the beam weight, a shaft journaled within said pipe and carrying a damper, a wheel affixed to said shaft outside the pipe and provided with a hub, a third chain suspended from the periphery of said wheel, and having a weight affixed to its lower end, a belt 95 around said hub and having one end secured thereto, a check-draft door for the furnace, a fourth chain led over a suitable pulley and connected with said belt and check draft door in such manner that the slackening of 100 said chain will effect the closing of said check draft door and opening of said damper, a fifth chain led over a suitable pulley and thence down around a pulley carried by the draft door and thence upwardly and secured to 105 said beam, and a thermostat connected to said fourth and fifth named chains to operate the same.

In testimony whereof I affix my signature 110 in presence of two witnesses.

WILBUR A. COMSTOCK.
